UNITED STATES PATENT OFFICE.

JOHN MERCIER, OF DETROIT, MICHIGAN.

CIDER-PRESS.

SPECIFICATION forming part of Letters Patent No. 249,852, dated November 22, 1881.

Application filed April 27, 1881. (No model.)

To all whom it may concern:

Be it known that I, JOHN MERCIER, of Detroit, county of Wayne, State of Michigan, have invented a new and useful Improvement 5 in Cider-Presses; and I declare the following to be a full, clear, and exact description of the same, such as will enable others skilled in the art to which it pertains to make and use it, reference being had to the accompanying 10 drawings, which form a part of this specification.

My invention consists in the combination of devices and appliances hereinafter set forth, and more particularly pointed out in the claims.

15 In the drawings, Figure 1 is a side elevation of a cider-press embodying my invention and showing portions by dotted lines. Fig. 2 is a separate view of one of the upper lags. Fig. 3 is a separate view of one of the lower lags. 20 Fig. 4 is a top view of the lower interior bearing detached.

This device is designed as an improvement on the device patented to me August 24, 1880, the improvement consisting, essentially, in 25 employment of an upper continuous belt of lags, made to travel in contact with an inner belt of anti-friction rollers, which latter travel in contact with a rigid interior bearing; and a similar lower series of lags, rollers, and 30 interior bearing. The two are so located with respect to each other that they present long flat opposing surfaces, which gradually approach each other, and as they travel forward they express the juice from the interposed pomace.

35 The invention also consists in a novel construction by which is effected the adjustment of a portion of one of the pressing surfaces to or from the other, and the adjustable portion is caused to close automatically upon the opposed surface in order to exert an efficient pressure when the pomace may be thinly laid or of soft consistency.

To this end, A is the frame. B B' and C C' are two sets of drums, over which the continuous 45 bands of lags D D' are adjusted. The drums B and C are geared together so as to travel at the same speed, and may be operated by a pinion, b, on the power-shaft b', to which may be attached any suitable driving means or 50 crank.

E E' are two continuous bands of anti-friction rollers, and F F' are rigid supports within the said bands.

G is a chute, which receives the juice as it falls and directs it out through any suitable 55 passage to the barrel or other receptacle designed to receive it.

H represents two rollers, and H' a continuous belt or cord passing over them, intended simply to support the sagging central portion 60 of the band of lags D'.

The operation of this portion of the device is, briefly, as follows: It will be observed that the opposed surfaces of the upper and lower bands of lags gradually approach each other, 65 and that the lower series extends back of the other some distance. This rear extension forms a feeding-table, upon which the fresh pomace is fed to the machine upon the lags D' in an even layer of uniform thickness. As the lags 70 D D' move forward in the direction of the arrows the pomace is subjected to a very great, but gradually increasing, pressure until it is eventually discharged in a dry state at D'. In this operation the pressure is sustained by the 75 rigid supports F F', and the anti-friction rollers E E' relieve the device of sliding friction and render it easy of operation.

The upper lags, D, are preferably made solid, with surface-recesses d, to facilitate the ready 80 discharge of the juice, and the rigid support F may or may not be made solid. The lower lags, D', however, should provide for the escape of the juice through them, and to this end they are preferably made of parallel pieces d', 85 separated by thin washers d², the whole being firmly bolted together; so, also, the rigid support F' is also preferably made of separate pieces f', with interposed blocks f², so as to permit the free passage of the juice through it 90 to the pan-chute G beneath. The lower lags, D', are shown as hinged together by links d³, which engage the bolts d⁴. The upper lags, D, are shown as hinged together by strap d³ and links d⁴. I would have it understood, however, that I do not limit myself to any particular means for fastening the lags together, nor 95 to any particular construction of the lags themselves.

In order to make the apparatus adjustable, 100

I propose to make the uprights in two pieces, I I', suitably held together—as, for instance, a loose mortise-and-tenon connection. I provide, also, bolts H² and nuts h², by which the parts 5 may be given any desired adjustment, so as to increase or diminish the space between the bands of lags. So, also, I propose to joint the rigid support F' at F² and hinge the adjacent parts together. A cross - piece, F³, will give

10 rigidity to the hinged portion when necessary.

I connect with the hinged section straps F⁴, which, extending through the top frame, are provided with a very stiff spring, f³, and an adjusting-nut, F⁵, by which a very considerable pressure may be exerted on the pomace in case there should happen to be a thin layer or the pomace should be of a soft consistency; but this spring would, in the ordinary use of the machine, yield so as to permit the hinged 15 section to rest on the cross-bar beneath.

Any suitable means may be employed for confining the pomace upon the lower lags, D', and to this end a canvas belt may be employed, with edges adapted to fold over the pomace; 20 but I do not lay any claim to any particular 25 means for the purpose.

What I claim is—

1. In a cider-mill, the combination of an upper continuous belt of lags, substantially as 30 described, passing over two drums, a separate inner continuous belt of anti - friction rollers supporting said belt of lags, and a rigid interior bearing supporting said belt of anti-friction rollers, with a similar lower belt of lags carried 35 by a belt of anti-friction rollers supported by an interior bearing, the opposite faces of said belts of lags converging, essentially as described.

2. The combination, with the top belt of lags, supported substantially as described, of 40 the lower belts of lags and rollers, the lower interior bearing formed of two parts hinged together, one fixed and the other movable, and means for adjusting said movable portion to bring the lower belt of lags in desired proximity to the upper belt, essentially as and for 45 the purpose set forth.

3. The combination, with the lower belt of lags and its supporting - belt of anti - friction rollers, of the interior bearing for said belt, 50 composed of the fixed and movable sections, the bolt-rod supporting said movable section, the spring surrounding the upper end of said rod, and the nut bearing upon said spring, substantially as described, and for the purpose 55 set forth.

4. The belt D, composed of the solid flexibly-connected lags having grooved pressing-faces, substantially as described.

5. The flexibly-connected lags D', formed of 60 separate parallel bars and interposed washers, substantially as described.

6. The combination, with the lower belt of flexibly-connected spaced or open lags, of the interior bearings, E, formed of separate parallel 65 bars and interposed blocks, substantially as and for the purpose set forth.

In testimony whereof I sign this specification in the presence of two witnesses.

JOHN MERCIER.
